TOWEL DISPENSING APPARATUS

Rudolph G. Birr, Lombard, Ill., assignor to
American Linen Supply Co., Carson City, Nev.,
a corporation of Nevada

Application November 3, 1948, Serial No. 58,030

8 Claims. (Cl. 242—55.5)

1

My present invention relates to apparatus for dispensing towels and aims to provide an apparatus which will be relatively easier to load and prepare for service than devices of this type heretofore provided.

My present apparatus is designed for the dispensing of paper towels from a roll but I do not limit myself to paper towels, as it will be apparent that my apparatus may also be used for dispensing fabric towels.

The principal object of the invention is to provide an apparatus of the kind described in which loading and conditioning the apparatus for dispensing is facilitated by the provision of a roll-holding structure which is swingable into and out of the cabinet for loading purposes.

It is an object of the invention to provide an apparatus of the character described in which means is provided to cooperate with the towel supply roll to minimize greatly the tendency of the roll to overspin when withdrawal of toweling is suddenly interrupted by the engagement of the members constituting a locking mechanism.

It is a further object of the invention to provide an apparatus of the character described in which a pressure member serves as a brake on the supply roll and in which said pressure member is provided with means, visible from the exterior of the apparatus, for indicating the quantity of towel available within the cabinet for dispensing.

It is a further object of the invention to provide an apparatus of the character described which will function properly only when a supply roll of the correct size is mounted in the apparatus and in which it will be difficult to withdraw toweling in the event that the apparatus should be loaded with a supply roll of insufficient axial length.

Other objects of the invention and the advantages thereof will be more fully brought out as the description proceeds.

In the accompanying drawings, I have illustrated a practical embodiment of my invention but it is to be understood that I do not limit myself to the precise structural features illustrated therein and described in the following specification. It will be readily apparent to those skilled in the art that the structural features are susceptible of embodiment in other forms without departing from the spirit of the invention or the scope thereof as defined in the appended claims.

In the drawings, Fig. 1 is a view in side elevation of a towel dis-

2

pensing apparatus embodying my invention, the cover being shown in open position and the roll-supporting structure swung out of the cabinet in loading position;

5 Fig. 2 is a view in side elevation with a portion of the cover broken away showing the stop mechanism in its inoperative position, said view being taken substantially on line 2—2 of Fig. 4;

10 Fig. 3 is a view similar to Fig. 2 but showing the stops engaged, said view being taken substantially on line 3—3 of Fig. 4;

Fig. 4 is a front elevation of the interior mechanism of the apparatus with the cover largely broken away;

15 Fig. 5 is a view in section taken substantially on line 5—5 of Fig. 4; and

Fig. 6 is a sectional view taken substantially on line 6—6 of Fig. 4.

Referring now to the drawings, the apparatus 20 comprises an inner casing made up of a back wall 1, side walls 2 and 3, and a bottom wall 4, thus providing a structure which is open at the front and the top. A cover 5 is pivoted as at 6 to the foregoing described casing and is swingable about 25 said pivots into the open position shown in Fig. 1. When the said cover 5 is in closed position, its sides will embrace and cover the side walls 2 and 3 and enclose the open top and front of the inner casing.

As shown particularly in Figs. 5 and 6, the bottom wall 4 of the inner casing is bent upwardly, near its forward end, as at 7, thereby providing with the front wall of the cover 5 a dispensing opening through which toweling may be withdrawn.

35 It will be noted that the front wall of the cover 5, near its bottom edge, is perforated as at 8 to provide openings through which the leading edge of the toweling may be seen from the front of the cabinet. This perforated area may be produced by stamping and, if desired, the letters of words may be stamped out, such as the words "tear here," as shown in Patent 2,298,179, granted October 6, 1942.

45 The towel feeding mechanism comprises a feed roll 9 journaled in the side walls 2 and 3. Said feed roll may be in the form of a grooved roll as shown particularly in Fig. 4 and may be covered with sandpaper or other friction material so as 50 to assure rotation of the roll as the towel is drawn across it.

At one end said roll is provided with a ratchet 10 cooperating with a pawl 11 mounted on the side wall 3 so as to prevent reverse operation of the feed roll 9.

At its opposite end the feed roll 9 is provided with a manually operable feed wheel 12. This feed wheel is provided so that a user may manually turn the feed roll so as to project the leading edge of the towel outwardly through the dispensing opening to make said leading edge accessible to the user who will grasp the same and draw the towel out. Said feed wheel 12 projects outwardly through a slot 13 formed in the front wall of the cover 5.

Cooperating with the feed roll 9 and also journaled in the side walls 2 and 3 is a pressure roll 14 which is pressed into contact with the feed roll 9 by suitable springs 15. Said pressure roll 14 is journaled in elongated slots 16 in the side walls 2 and 3 so as to provide room to lift the pressure roll 14 out of contact with the feed roll 9 when the apparatus is being loaded.

A guiding apron 17 is mounted on the pressure roll 14 and extends downwardly in contact with the surface of the feed roll 9, thus forming a dispensing throat through which the towel passes when it is being withdrawn from the cabinet.

Said apron 17 is provided with straps 18 which extend over the pressure roll 14. These straps are provided with small and somewhat sharp projections 19 for a purpose presently to be described.

The upwardly bent portion 7 of the bottom wall 4 may be provided with a plurality of stripper fingers 20 adapted to engage in the grooves of the feed roll 9 and are so arranged with respect to the surface of said feed roll 9 that they prevent the toweling from becoming wrapped around said feed roll and assure delivery of the toweling through the dispensing throat.

It will be noted, particularly from an inspection of Figs. 5 and 6, that the feed roll 9 and the pressure roll 14 are arranged in the lower part of the cabinet and near the front thereof.

As will also be seen from said Figs. 5 and 6, the supply roll-supporting structure is mounted above the feeding mechanism and comprises the following arrangement: Roll-holding arms 21 are pivoted as at 22 to the side walls 2 and 3 and said arms are adapted to be swung about said pivots 22 to a position outside of the cabinet as shown in Fig. 1.

The lower edges of the arms 21 are bent over as at 23 and are connected by a strap 24 which preferably is resilient so as to permit slightly spreading the arms 21 when they are in loading position outside of the cabinet and thus facilitate the proper insertion of a supply roll.

The arms 21 are provided with journals 25 which are adapted to enter into the usual hollow core upon which the supply roll is wound.

If desired, the journals 25 may be provided with a control device adapted to cooperate with a similar device provided on the core of the roll so as to assure that only proper rolls may be mounted in the cabinet. This arrangement may be of the type shown in Patent 2,169,399, granted August 15, 1939. Because of the disclosure of this earlier patent, I deem it unnecessary here to elaborate upon that particular mechanism which forms no part of my present invention.

The arms 21 are provided with laterally extending wing members 26 which are adapted to engage the front edges of the side walls 2 and 3 so as to limit inward movement of said arms and the roll supported thereby and provide for accurate placement of the supply roll.

In the drawings said supply roll is indicated by the reference numeral 27 and may be, and preferably is, a roll of paper toweling although a roll

of fabric toweling may also be mounted in my apparatus and dispensed thereby.

The said wing members 26 also serve to limit outward movement of the supporting arms 21 when they are in position to be loaded with a supply roll, as shown in Fig. 1.

It is to be noted from Figs. 5 and 6 that when the supply roll 27 is in proper position and the cabinet is ready for dispensing, said supply roll is located above the feed apparatus comprising the rolls 9 and 14.

Because in my present apparatus it will be desirable to use a stop mechanism which will presently be described, it sometimes happens that when rotation of the supply roll is suddenly interrupted, there is a tendency for the roll to overspin and thus produce a loop of toweling within the cabinet. In order to prevent, or at least to minimize, this occurrence, I provide a pressure member 30 pivotally mounted in the side plates 2 and 3 by pivot pins 31 and which is held against the supply roll 27 by springs 32.

The pressure member 30 is provided along its outer edges with flanges 33 which aid in centering the supply roll in the cabinet and prevent any possible lateral shifting of the roll.

It will be seen from an inspection of Figs. 5 and 6 that the center of gravity of the supply roll 27 is well inside the cabinet beyond the pivot point 22 and that the pressure member 30 bears against the back surface of the roll. There will thus be sufficient pressure on the roll to prevent overspinning or at least to reduce such overspinning to a minimum so that proper operation of the device is not hindered.

If it should be attempted to load the apparatus with a supply roll of insufficient axial length to be supported by the arms 21, such shorter roll will then necessarily be supported on the pointed projections 19 formed on the straps 18 which surround the pressure roll 14. Said pointed projections 19 will therefore indent the paper on the supply roll and prevent its rotation so that toweling cannot be withdrawn from the cabinet.

To the back of the pressure member 30 I have secured an indicator 34. Said indicator is visible through a slot 35 formed in the cover 5. Suitable indicia may be stamped or otherwise marked along the slot so that the position of the indicator 34 will indicate the amount of toweling that remains in the cabinet, thereby to inform the attendant when it is necessary to re-load the apparatus.

It is understood, of course, that as the diameter of the supply roll 27 decreases by reason of withdrawal of toweling the pressure member 30, by reason of the springs 32, follows the roll and remains in contact therewith. Therefore, the said indicator 34 will substantially accurately indicate the amount of the supply roll that is still within the cabinet.

In a dispensing apparatus of this sort used for the purpose intended, it is desirable to eliminate as far as possible the wasteful use of toweling. To this end my apparatus is provided with a stop mechanism which becomes operative after a predetermined length of toweling has been withdrawn to lock the feed roll against further rotation.

It is also desirable that the mechanism shall remain engaged for a predetermined length of time so as to prevent too rapid successive withdrawals. To this end, I have incorporated a

time control mechanism which will now be described in conjunction with the stop members. A stop member 40 is mounted on the journal of the feed roll 9 to rotate therewith. A second stop member 41 is pivoted on the side plate 3 as at 42 and is provided with a spring 43 which tends to hold the stop member 41 in its inoperative position. A slotted link 44 connects the two stop members and is so arranged that as the feed roll 9 is rotated the rotative movement of the stop 40 will pull the pivoted stop 41 into locking position. Fig. 2 shows the stop members in their normal inoperative position so that the feed roll 9 may be freely rotated. Fig. 3 shows said members engaged so that rotation of the feed roll 9 is prevented.

The time control mechanism comprising a pair of vacuum cups 45 and 46. The lower cup 45 is mounted on a plate 47 which is secured to the side plate 3. The upper vacuum cup 46 is mounted on a slide 48 which has a guide slot 49 engaging a pin 50 on the side plate 3. The slide 48 is also held in position by the fixed plate 47. The bottom of the slide 48 carries a link 51 which is connected to the slotted link 44 at its pivot point 52 on the movable stop 41.

The foregoing arrangement is such that as the movable stop 40 rotates upon rotation of the feed roll 9 the cooperative action of the links 44 and 51 will pull the slide 48 downwardly and press the vacuum cup 46 into engagement with the vacuum cup 45, as shown in Fig. 3. Said vacuum cups are held together by the vacuum thus created and will not separate until sufficient air is allowed to enter into them. The entrance of air is controlled by a valve 53 carried by the vacuum cup 45. This valve is adjustable so that the length of time that the cups remain vacuum-attached may be regulated for almost any desired length of time from about one second to as long a time as is desired.

When air enters into the evacuated space between the cups, the vacuum attachment is broken and the spring 43 will rock the pivoted stop member 41 about its pivot 42 and thus restore the slide 48 to its initial inoperative position.

The stop mechanism and time-control therefore which have been described above are substantially identical with the corresponding mechanisms shown in my copending application, Ser. No. 722,590, filed January 17, 1947, now Patent No. 2,592,786, dated April 15, 1952. In this respect, the present application may be considered a continuation in part of my said former application. Parts of the paper ejection after a timed stop is disclosed in my copending application 544,919 filed July 14, 1944, now Patent 2,457,439, dated December 28, 1948, of which this may be considered a continuation in part.

It will be noted from an inspection of Figs. 2 and 3 that the movement of the slide 48 is in a straight vertical line and that the engagement of the stops 40 and 41 is on a line substantially centrally of the slide 48. By this straight line motion and contact of the stop members, I eliminate to a great extent wear on these parts normally experienced by other arrangements.

From an inspection of Figs. 1 and 4, it will be seen that the manually operated feed wheel 12 is provided with a wire bale 55 connected to a coil spring 56 secured to a flange formed on the side plate 2. The purpose of this arrangement is to provide an automatic feed-out of toweling when the time stop mechanism previously de-

scribed disengages at the end of the predetermined time interval. When toweling is withdrawn the said feed wheel 12 rotates with the feed roll 9, thus stretching the spring 56. But said spring cannot retract so long as the stop mechanism remains engaged. When the stops 40 and 41 separate and the feed roll 9 is free for rotation, the spring will retract and will cause a rotative movement of the feed roll 9 sufficient to expose the leading edge of the toweling and make it accessible to the user. The foregoing described automatic feed mechanism is also illustrated in my said copending application, Ser. No. 722,590. It will be understood, of course, that the automatic feed mechanism just described is not necessarily employed in this apparatus. It may be eliminated by omitting the bale 55 and the spring 56 so that the manually operated feed wheel 12 is used alone to advance the toweling into position to be grasped.

To service this apparatus, an attendant first unlocks the lock 60 by which the cover 5 is held in position over the dispensing mechanism. Said cover 5 is then lowered to the position shown in Fig. 1. The attendant now swings the roll supporting arms 21 out of the cabinet and may use the laterally projecting wings 26 for that purpose. The arms 21 may be spread slightly so as to facilitate the insertion between them of a supply roll, such spreading being permitted by the resilient strap 24 which connects the arms. When in this position, the leading edge of the toweling is pulled down and passed between the feed roll 9 and the pressure roll 14, the latter being raised slightly against the action of the springs 15 to permit passage of the toweling. At this time also the apron 17 may be lifted slightly so that the toweling may freely pass down into the dispensing throat. This having been done, the arms 21 are swung back into the cabinet as shown in Figs. 5 and 6 and the lock 60 is closed. The cabinet is now ready for operation.

When loading the cabinet, a sufficient length of toweling is drawn over the feed roll and through the dispensing opening so that the leading edge of the toweling may be grasped and pulled. When this is done, the feed roll is rotated until the stops engage and prevent further rotation. The length of toweling thus withdrawn is torn off along the bottom edge of the cover.

At the end of the timing period provided by the vacuum cup mechanism, the stops disengage and the feed roll is again free to rotate. At this time the said feed roll will be slightly rotated by the retraction of the spring 56, if the automatic feed-out is used, so as to make the leading edge of the toweling again accessible for grasping by the user.

If the automatic feed-out mechanism is not used, it is necessary only to rotate the manually operable feed wheel 12 slightly so as to bring the leading edge of the toweling into position to be grasped.

I claim as my invention:

1. Towel dispensing apparatus comprising a casing having a delivery opening, a feed roll in said casing, a pair of supply roll supporting arms pivotally mounted in said casing for swinging movement into and out of said casing, and means on said arms for limiting swinging movement in both directions.

2. Towel dispensing apparatus comprising a casing, a pair of supply roll supporting arms pivoted at one end to said casing near the front thereof, roll supporting journals on the opposite ends of said arms, and resilient brake means

at the rear of said casing adapted to bear against a supply roll mounted in said journals.

3. Towel dispensing apparatus comprising an inner casing and a cover therefor, a pressure member pivotally mounted in said inner casing and adapted to bear against the cylindrical surface of a supply roll and having means adapted to resist axial motions of the supply roll, said cover being provided with an opening through which the position of said pressure member may be observed to determine the necessity of reloading the casing.

4. Towel dispensing apparatus comprising an inner casing and a cover therefor, said cover being provided with a sight opening, a brake pressure member pivotally mounted in said casing and adapted to bear against the cylindrical surface of a supply roll, and means on said pressure member visible through said sight opening for indicating the diameter of the supply roll and the necessity of replacing the same.

5. Towel dispensing apparatus comprising a casing, a pair of arms in said casing for supporting a supply roll of predetermined axial length, a pressure roll in said casing below said supply roll, and means on said pressure roll adapted to engage and prevent rotation of a supply roll of insufficient axial length to be supported by said arms.

6. Towel dispensing apparatus comprising a casing, a feed roll mounted therein, a pressure roll contacting said feed roll, a guide apron secured to said pressure roll and forming with said feed roll a passage for toweling, means in said casing for supporting a supply roll of predetermined axial length, and means on said guide apron securing means for engaging and preventing rotation of a supply roll of less than said predetermined axial length.

7. Towel dispensing apparatus comprising a

5
10

casing, means for supporting a roll of toweling in said casing, a feed roll over which the toweling passes and adapted to be rotated by a pull on the toweling, means for locking said feed roll against further rotation after the delivery of a predetermined amount of toweling, timing mechanism for holding said locking means engaged and permitting its disengagement after the lapse of a predetermined time interval, a manually operable feed wheel for rotating said feed roll, and means on said feed wheel for automatically rotating said feed roll when said locking means disengages.

15
20
25

8. Towel dispensing apparatus comprising a casing, a feed roll in said casing adapted to be rotated by a pull on the toweling, a manually operable feed wheel connected to said feed roll and accessible from the exterior of said casing, and spring means in said casing connected to said feed wheel for automatically partially rotating said feed roll.
